SPICE CHEST CABINET

Donald J. Booty, Frankfort, Ill., assignor to Amico, Inc., Philadelphia, Pa.

Filed Apr. 17, 1974, Ser. No. 461,680

Term of patent 14 years

Int. Cl. D6—04

U.S. Cl. D6—129

FIG. 1

FIG. 2

FIG. 3

FIG. 4

FIG. 5

FIG. 1 is a front elevational view of a spice chest cabinet showing my new design;

FIG. 2 is a right side elevational view, the left side being a mere image thereof;

FIG. 3 is a rear elevational view;

FIG. 4 is a top plan view; and

FIG. 5 is a bottom plan view.

I claim:

The ornamental design for a spice chest cabinet, substantially as shown and described.
